UNITED STATES PATENT OFFICE

KURT DIENER, OF GORKE, NEAR ANKLAM, POMERANIA, GERMANY, ASSIGNOR TO THE FIRM N. V. UNION MAATSCHAPPIJ VOOR AUTOMATISCHE METAALBEWERKING, OF ROTTERDAM, NETHERLANDS

FIREARM

Application filed December 22, 1928, Serial No. 327,864, and in Germany December 22, 1927.

The present invention relates to firearms and more particularly to an improved stock or butt-end in connection with a gun or rifle.

5 In the firearms as hitherto produced or designed the breech and the lock mechanism are usually united immediately with the butt-end and by carving the latter recesses and cavities are formed therein for the accommodation of the assembled parts of the lock mechanism, so that the stationary members or constituent parts thereof fit snugly therein while the recesses or cavities thus produced for the reception of the movable members thereof afford a smallest possible clearance, only in order that a largest possible cross-sectional area may be maintained at the fore-end of the stock for the purpose of 15 withstanding external stresses to which firearms of the stated kind are subjected in handling.

As a result thereof the inner parts of the lock mechanism are not readily accessible and in order to gain access thereto it is necessary to remove the stock from the firearm which is very inconvenient and troublesome. Especially in case of sporting guns and rifles which require a butt-end of neat and graceful configuration, the space available for 25 the accommodation of the lock mechanism is inadequately confined due to the given or desirable maximum cross-section of the fore-end of the stock, but although the wooden body of the stock is highly preserved in 30 this way, still the carved or recessed end thereof is excessively weakened so as to give rise to damage and breakage. The chief object of my invention is to remedy this defect.

40 With this end in view my invention consists in providing between the breech and the fore-end of the wooden stock a chamber for the reception of the lock mechanism, said chamber being confined by a top plate and 45 by a bottom plate, both plates bridging the interstice between bridge and stock and rigidly connecting them, while the said chamber is laterally closed by two detachable parts. The said bottom and top plates 50 or bars are larger and of greater thickness

than the plates hitherto employed in firearms of the stated kind for inter-connection of the breech and the stock. The detachable lateral parts or walls of the chamber can be made of wood partially or totally so as to constitute with regard to outer appearance a continuation of the wooden stock and making it resembling the usual structure and configuration of the stocks of firearms as hitherto produced.

55 The detachable lateral walls of the lock chamber may be so dimensioned that when detached the frontal essential parts of the lock mechanism only will be visible and readily accessible or, alternatively, they may be of a size to extend sufficiently far towards the rear to expose when removed all underlying parts of the lock mechanism inclusive of the safety device, the transposing device and the trigger mechanism.

60 For the purpose of increasing the rigidity and firmness of the structure and reducing at the same time the size or area of the detachable lateral walls, particularly as regards the vertical width thereof, I prefer to 70 shape either the top bar or the bottom bar or both so as to somewhat project with their free edges towards the centre of the side openings into which the detachable lateral walls are to be inserted, but without impairing the accessibility of the lock mechanism in the chamber. It will be understood 75 that in this way the inter-connection accomplished between the breech or barrels and the stock of the arm by means of the 80 said plates will be considerably reinforced while at the same time the size of the lateral openings of the chamber can be so much reduced thereby that plain pieces of sheet metal or the like may be used for closing 85 the said openings. The means required or preferred for locking the closing pieces, members or walls in their closing positions may be of any conventional type such as small levers, sliding studs or the like adapted 90 to be manually operated without the necessity of employing any tools.

95 I will now proceed to describe my invention more in detail in connection with the several embodiments thereof, illustrated 100

somewhat diagrammatically on the accompanying drawings, it being understood that the invention is limited to the embodiments thereof as illustrated and described.

5 In the accompanying drawings forming a part of this specification and showing, for purposes of exemplification, three preferred forms and manners in which the invention may be embodied and practised.

10 Figure 1 is a side elevation of that portion of a sporting gun to which the invention is applied, the muzzle end of the barrels and the rear extremity of the stock being broken away;

15 Figure 2 is a plan of one of the two detachable lateral wall-members;

Figure 3 is a view in top plan of the gun shown in Figure 1 with the two lateral walls being removed;

20 Figures 4, 5 and 6 are views similar to Figures 1 to 3 respectively, showing another embodiment or modification of the invention; and Figure 7 is a side elevation of a third embodiment.

25 In all these embodiments shown in the drawings the fore-end of the stock terminates in a transversal plane indicated by the line A—B, and the breech member of the gun is firmly connected with the stock by means of a top bar 13 and a bottom bar 14.

30 Referring more particularly to the embodiment shown in Figures 1 to 3 the reference characters 1 and 2 indicate the detachable lateral walls or shells shaped to fit in and close the side openings of the chamber formed between the bars 13 and 14 and adapted for the accommodation of the lock mechanism. As will be seen in Figure 2, the shell comprises a wooden member or shell 35 properly speaking, and a steel plate 8 having a T-shaped trail 12 sunk in the correspondingly recessed wooden shell and firmly attached to the latter by means of screws, rivets or the like 9, 10 and 11. The extremities of the two arms of the T-shaped trail 12 are shaped to form lugs 5 and 6 respectively adapted to engage with the upper bar 13 and the bottom bar 14 for connecting purposes and the two bars 13 and 14 45 are in turn provided each with an inwardly projecting nose 3 and 4 respectively for engaging connection with the stock.

50 When the stock of the gun is shaped like the butt-end of a pistol a bore 7 is to be provided therein for the reception of the bottom bar 14 as shown in Figures 1, 4 and 7.

55 In the modification illustrated in Figures 4 to 6 an undivided coherent shell *s* made of steel or any other appropriate metal is substituted for the combined shell composed of a wooden part and a metallic part as shown in Figure 2. In some cases I prefer, however, to cover the outer face of the metallic shell *s* with a suitable veneer. This modi-

fication involves a considerable enlargement of the chamber for the accommodation of the lock mechanism so that the constituent members of the latter can be given a higher degree of resistance against wear and breakage by increasing certain dimensions thereof.

70 Furthermore in the embodiment shown in Figures 4 to 6 the lateral clamping projections or noses 3 and 4 of the top bar 13 and the bottom bar 14 respectively are elongated to form semicircular rings or segments *r* cooperating to enclose and cover the joint at the fore-end of the wooden stock, indicated by the dash-and-dot line A—B 75 80 and to ensure the interconnection of the two shells and the stock.

85 In the embodiment shown in Figure 7 the top bar 13 and the bottom bar 14 are enlarged in width and shaped to form lateral flanges in the manner of a vaulted structure adapted to partially enclose and laterally cover the chamber for the accommodation of the lock mechanism as clearly shown with relation to the top bar 13 in Figure 7. In this way the 90 rigidity and strength of the connection between the breech and the stock are considerably increased and at the same time the surface area of the shells *s* can be correspondingly reduced so that the latter can more conveniently be made of metal only in the shape of an undivided coherent plate.

95 As shown in Figure 7 the covering shells or plates *s* are pivotally connected with the bottom bar 14 so that the chamber can be 100 opened for access to the lock mechanism by turning the plates *s* about their pivots 15.

What I claim is:

1. In a firearm of the character referred to the combination of a breech structure, a wooden stock whereof the fore-end terminates a distance remote from and behind the body of the breech to form a chamber for the accommodation of the lock mechanism therebetween top and bottom bars in firm connection with the said breech structure and stock, the two bars constituting the top wall and the bottom wall respectively of the said chamber and two detachable plates or shells constituting the side walls of the said chamber.

110 2. In a firearm of the character referred to the combination of a breech structure, a wooden stock whereof the fore-end terminates a distance remote from and behind the body of the breech to form a chamber for the accommodation of the lock mechanism therebetween top and bottom bars in firm connection with the said breech structure and stock at least one of said bars being vaulted so as to partly cover said lock chamber and reduce the area of its free lateral opening and two detachable plates or shells constituting the side walls of the said chamber.

115 3. A lateral cover for the lock chamber of

the firearm of claim 1 consisting partly of wood and partly of metal, the cover provided with interconnecting means for detachable connection with the arm and the wooden portion thereof forming a continuation of the wooden stock.

5 In testimony whereof, I affix my signature.
KURT DIENER.
